UNITED STATES PATENT OFFICE.

FRANK F. FORTNEY AND THOMAS H. STEVENS, OF RAVENNA, OHIO; SAID FORTNEY ASSIGNOR TO SAID STEVENS.

DENTAL CHIN-REST.

SPECIFICATION forming part of Letters Patent No. 591,338, dated October 5, 1897.

Application filed August 7, 1896. Serial No. 601,968. (No model.)

To all whom it may concern:

Be it known that we, FRANK F. FORTNEY and THOMAS H. STEVENS, of Ravenna, Portage county, Ohio, have invented certain new and useful Improvements in Chin-Rests; and we do hereby declare the following to be a full, clear, and exact description of the invention, such as will enable others skilled in the art to which it pertains to make and use the same.

Our invention relates to improvements in chin-rests designed more especially for use in dental parlors in operations upon the teeth of the patient's lower jaw; and it consists in certain features of construction and combinations of parts hereinafter described, and pointed out in the claims.

In the accompanying drawings, Figure 1 is a front view of a chin-rest embodying our invention. Fig. 2 is a left-hand side elevation of the same, showing the device applied to the chin of the patient. A portion of the pad or cushion in which a plate to which the chin-rest is embedded is broken away and said plate shown in section. Fig. 3 is a side elevation, mostly in central section, of a chin-rest embodying our invention.

Referring to the drawings, A designates the chin-rest proper that consists, preferably, of a plate arranged to afford bearing for the under side of the chin and bent or flanged upwardly at each side, as at A', to afford lateral bearing for the chin, and bent or flanged upwardly also at the front, as at A², to afford an abutment or bearing for the forward side of the chin.

In Fig. 2 of the drawings said device is shown applied to the chin of the patient. The chin-rest proper is preferably supported from a plate B, that is suitably attached to and preferably embedded within the pad or cushion C, designed to rest against the bust of the patient and provided with a strap or band C' or other means instrumental in suspending said cushion or pad from the neck of the patient. Another plate D is detachably secured, preferably by means of screws d, to plate C and is provided with a forwardly-projecting arm D'.

Another and suitably-curved arm or bracket E is connected at one end with the forward

end of arm D' by means of a ball-and-socket joint so arranged that bracket or arm E cannot only be turned but tilted vertically and laterally in opposite directions. In Fig. 1 of 55 the drawings the ball of the ball-and-socket joint is formed upon arm D', whereas in Fig. 3 the ball is formed upon arm D' and the socket upon bracket or arm E.

The chin-rest proper is suitably supported 60 from the opposite or rear end of arm or bracket E. The latter extends upwardly and rearwardly from arm D', and at its upper and rear end is connected with the chin-rest proper in such a manner that the latter (the chin- 65 rest proper) can be tilted rearwardly and forwardly and can also be turned or adjusted horizontally. In Fig. 1 a U-shaped piece G has its lower and central member swiveled at 70 g to the upper end of arm E, and an arm or member H, bearing the chin-rest proper and depending from the latter, is horizontally pivoted to and between the end members of said U-shaped piece. By this construction it will be observed that the chin-rest proper can be 75 turned upon arm or bracket E and can also be swung forwardly and rearwardly in a vertical plane, and hence is capable of accommodating itself to the position of the patient's chin.

In Fig. 3 the arm H, that bears the chin-rest proper, is connected with the upper or rear end of arm or bracket E by means of a ball-and-socket joint. The socket of said joint is formed upon bracket or arm E, and the ball 85 of the joint is formed upon arm H. By this construction the chin-rest proper cannot only be turned horizontally and has a limited capability of being swung forwardly and rearwardly in a vertical plane, but has also a limited 90 movement laterally in opposite directions.

If desired, set-screws I, as shown in Figs. 2 and 3, can be provided for securing the movable members of the ball-and-socket joints in 95 the desired adjustment, and the sockets of said joints are provided with screw-threaded holes for receiving said screws.

What we claim is—

1. The combination of a pad or cushion, a 100 plate attached to the cushion or pad and provided with a forwardly-projecting arm or

member, an upwardly and rearwardly extending arm connected with the forward end of the aforesaid forwardly-projecting member, and the chin-rest proper supported from the upper end of said rearwardly-extending bracket or arm, substantially as shown and described.

2. The combination of a pad or cushion, a plate attached to the cushion or pad and provided with a forwardly-projecting member, a rearwardly and upwardly extending laterally-swinging arm or bracket supported from the aforesaid forwardly-projecting member, and the horizontally-rotating and vertically-tilting chin-rest proper supported from the upper end of said rearwardly-extending bracket or arm, substantially as shown and described.

3. The combination of a pad or cushion, a plate attached to the cushion or pad and pro-

vided with a forwardly-projecting member, 20 a rearwardly and upwardly extending arm or bracket connected, at its lower end, with the aforesaid forwardly-projecting member by means of a ball-and-socket joint, the chin-rest proper, an arm or piece bearing the chin-rest proper and supported from the aforesaid rearwardly-extending arm or bracket and connected with said bracket or arm by means of a ball-and-socket joint, substantially as shown and described. 25

In testimony whereof we sign this specification, in the presence of two witnesses, this 1st day of August, 1896.

FRANK F. FORTNEY.
THOMAS H. STEVENS.

Witnesses:

C. H. DORER,
ELLA E. TILDEN.
